RAILWAY TRAFFIC CONTROLLING APPARATUS

Lloyd V. Lewis, Edgewood, Pa., assignor to The Union Switch & Signal Company, Swissvale, Pa., a corporation of Pennsylvania

Application February 16, 1928, Serial No. 254,639

82 Claims. (Cl. 246—3)

My invention relates to railway traffic controlling apparatus, and particularly to apparatus for safely controlling traffic governing devices, such as railway switches and signals from a remote point, such for example, as a train dispatcher's office, and for also indicating the conditions of such devices at said office.

The apparatus of my invention is particularly adapted for use in centralized traffic control systems for railroads, and is an improvement over that disclosed in a copending application Serial No. 254,684, filed Feb. 16, 1928, by Clarence S. Snavely, for Railway traffic controlling apparatus, and also upon that disclosed in a copending application Serial No. 362,948, filed May 14, 1929, by the said Clarence S. Snavely, for Remote controlling apparatus.

I will describe one form and arrangement of railway traffic controlling apparatus embodying my invention, and will then point out the novel features thereof in claims.

In the accompanying drawings, Figs. 1, 2, and 3, when placed end to end in the order named with Fig. 1 on the left, comprise a diagrammatic view illustrating one form of railway traffic controlling apparatus embodying my invention.

Referring to the drawings, the apparatus embodying my invention includes a master synchronous selector located at a control point such as for example as the dispatcher's office and illustrated on Fig. 1 of the drawings. This equipment is connected by means of four line wires with a plurality of way station synchronous selectors located at spaced stations along a stretch of trackway. These selectors by their synchronous operation serve to establish sequentially a series of intermittently available message channels for communication between the office and the several stations. In the form here shown, the system is designed for controlling apparatus located at seven stations, but this number is not essential.

In general terms, the apparatus comprises a pole-changer relay located at the dispatcher's office which is effective when operated to send a succession of impulses over a stepping line circuit comprising two of the line wires to all of the stations simultaneously. Located at the office is a series of stepping or counting relays, and a similar series of counting relays is located at each station. When the pole changer relay is operated, the counting relays at the office and at each of the stations are successively energized in synchronism and these counting relays are arranged to successively connect controlling and indicat-

ing apparatus at the several stations with corresponding apparatus at the office over message circuits including certain of the line wires, and hence serve as channel selecting relays. The controlling and indicating apparatus located at each station may co-operate with traffic governing devices of any suitable type but as here shown the system is intended for controlling railway switches and signals and for returning to the control office indications of the conditions of the switches and the associated track sections at the several stations.

Referring now more in detail to the apparatus shown, the reference character Q designates a pole changer relay comprising a pair of stepping windings 6 and 7 and an armature 8 arranged to be swung in one direction or the other depending upon which of the associated windings is energized. Relay Q is controlled by a relay T¹ in such manner that when relay T¹ is de-energized, current flows from terminal x⁰ of a suitable source of energy not shown in the drawings, through back contact 9 of relay T¹, wires 10 and 11, and winding 6 of relay Q to terminal y⁰ of the same source. When relay T¹ is de-energized, therefore, winding 6 of relay Q is constantly supplied with energy and armature 8 of the relay is swung to the left. When relay T¹ becomes energized, however, terminal x⁰ is connected with the polar contact 12 of relay Q over front contact 9 of relay T¹. Under these conditions, if the armature 8 occupies its left-hand position, current is supplied to winding 7 of relay Q. As a result, the armature 8 swings to the right, thereby interrupting the circuit for winding 7 and closing the circuit for winding 6, whereupon the relay swings its armature back to the left and again establishes the circuit for winding 7. It follows that with relay T¹ energized, the relay Q operates continuously to swing its contacts alternately to one extreme position or the other. The pole changer relay Q controls a bank of office counting relays each designated by the reference character OM with a distinguishing suffix. The operation of the relays OM will be described in detail hereinafter.

Associated with relay T¹ is a relay T², which is arranged when energized to connect polar armature 13 of relay Q with a stepping line wire 14 over front contact 15 of relay T². The line wire 14 together with line wires 16, 17 and 18 extend throughout the system and communicate with each of the stations. The relays T¹ and T² are controlled by a line relay L in such manner that when relay L is de-energized, current flows from

terminal x^0 , through back contact 19 of relay L, through winding of relay T² directly to terminal y^0 . Current also flows from terminal x^0 , through back contact 19 of relay L and winding 5 of relay T¹ to terminal y^0 over back contact 20 of relay OM8.

The control office is also provided with a starting relay OP and a transfer relay OB, the operation of which will be apparent as the description 10 proceeds. The reference character 21 designates a pilot lamp which is arranged to be energized when back contact 22 of relay T² is closed to indicate that the apparatus occupies its normal position.

15 Located also at the control office are a plurality of panels one corresponding to each station which is controlled from the office. Each panel is designated by a number which corresponds to the number of the station associated therewith, panel 20 number 1 corresponding to station number 1, being the only panel which is illustrated complete in the drawings. Each panel is provided with certain equipment which will be referred to in detail hereinafter.

25 Located at each station is a set of equipment comprising a synchronous selector which at times is controlled over the stepping line wire 14 to establish communication with the office over the message line wires 16 and 17 and the common 30 return wire 18, the equipment located at stations 1 and 7 only being shown complete in the drawings to illustrate the invention. Each station is provided with a centrally biased three position polarized line relay each designated by the 35 reference character D with a prefix corresponding to the location. Each relay D is arranged when deenergized to occupy an intermediate position and to respond to current of one polarity or the other to swing its contact in one direction or the 40 other. Each relay D controls a bank of counting relays similar to the counting relays at the dispatcher's office and each designated by the reference character M with a prefix corresponding to the location and a distinguishing suffix. 45 Certain other relays are located at each station and are arranged to operate in a manner which I will describe in detail when I explain the operation of the apparatus as a whole.

It should be noted that line wire 18 is a common 50 wire for the office and all stations, and that this wire is connected with the midpoints of a plurality of line batteries one at the office and one at each station and each designated by the reference character Z with a prefix corresponding 55 to the location. In order to simplify the drawings, I have designated the terminals of each line battery by a reference character comprising the reference character of the battery and the suffix X or Y for the positive and negative terminals, 60 respectively. In addition each station is provided with a local battery not shown in the drawings but having terminals designated by the reference characters x and y with appropriate distinguishing exponents corresponding to the 65 location.

The equipment at each station also comprises a switch control relay designated by the reference character W with a prefix corresponding to the 70 location and three signal control relays designated by the reference characters H, F and G, respectively, with suitable distinguishing prefixes. Each station is further provided with a track detector relay and a switch detector relay designated by reference characters RA and WA, re-

spectively, with prefixes corresponding to the locations.

The equipment at each station is arranged to control traffic governing apparatus which in the form here shown comprises a switch 3 for connecting a siding 4 with a main track, the rails 1 and 1^a of which are divided by means of insulated joints 2 to form a track section including each such switch. Referring particularly to the apparatus located at station 1, the section a—b 5 is provided with a track relay designated by the reference character 1R connected across the rails adjacent one end of the section. A track battery 5 connected across the rails adjacent the opposite end of the section normally energizes relay 1R 10 but this relay is deenergized when a train occupies the section. The rails of the siding 4 adjacent the switch 3 are connected with the rails of section a—b 15 in accordance with the usual practice so that a train occupying a siding 4 to the left of point b will also de-energize relay 1R.

The switch 3 at station 1 is operated by a motor 1E comprising an armature 28 and a field 29. The motor 1E is controlled in part by the switch control relay 1W and by a circuit controller 25 1C comprising a plurality of double throw contactors each comprising a movable member co-operating with two stationary contacts and controlled in accordance with the position occupied by the switch. When the switch occupies its 30 normal position, in which it is illustrated in the drawings, contacts 38—38^a, 37—37^a, 36—36^a and 35—35^a are closed. When the switch is reversed, however, contacts 38—38^b, 37—37^b, 36—36^b and 35—35^b are closed. Furthermore, the circuit controller 35 1C comprises a contact 24—24^a which is closed at all times except when the switch occupies its reverse position, and a second contact 24—24^b which is closed at all times except when the switch occupies its normal position.

Relays RK, WK, RA, WA, W, F and G, are all polarized stick relays of the snap-action type. The armature of each of these relays constitutes a double-throw contactor cooperating with two stationary contacts, and these relays are constructed in such manner that their armatures remain in the positions to which they were last moved until they are positively moved in the opposite direction. In discussing each of these relays, I will consider the relay to be energized 45 in its normal direction when the armature of the relay is swung to the right, and in the reverse direction when the armature is swung to the left.

In describing the operation of the apparatus as a whole, it should be pointed out that as shown 50 in the drawings, the sections of track associated with stations 1 and 7 are unoccupied and it is assumed that the apparatus located at the remaining stations is similar in all respects to the apparatus located at stations 1 and 7. The track 55 switches 3 located at each station occupy their normal positions and all polarized stick relays have been energized in their normal directions, so that relays RA are in agreement with the normally energized track relays R and relays WA 60 are in agreement with the track switches 3. The polarized line relays D are de-energized so that the polar armatures of these relays occupy intermediate positions. All relays at each station are de-energized except the relay S at each station. 65 Referring particularly to the apparatus located at station 1, relay 1S is held energized by current which flows from terminal x^1 over back contact 49 of relay 1U, wire 115, and relay 1S to terminal y^1 . In similar manner, the relay S associated 70

with each of the remaining stations is energized over a corresponding back contact of the relay U at such station.

At the dispatcher's office, all relays are de-energized except relays Q and L. As has already been explained, since relay T¹ is de-energized, winding 6 of relay Q is continuously energized so that the armature contacts of this relay are swung to the left. Furthermore, relay L is held energized over a normally closed line circuit which may be traced from terminal OZX of line battery OZ, through back contact 50 of relay OP, wire 51, winding of relay L, wire 52, back contact 53 of relay T¹, to line wire 17 and thence over a back contact 54 of relay IP at station 1, wire 55, back contact 56 of a selector relay IJ located at station 1 and thence through back contacts of each relay P and each relay J at each of the remaining stations, returning to battery OZ over line wire 18. Since the relays P and J at each station are now de-energized, the circuit just traced for relay L is closed and this relay is energized. It should be noted that since relay T² is de-energized, the circuit for pilot lamp 21 is closed and this lamp is lighted to indicate that the apparatus occupies its normal condition.

If under these conditions, a train enters any of the track sections located at the several stations so that a track relay R is moved to a position out of agreement with its associated relay RA or if any of the switches 3 located at the several stations is reversed, so that its position does not agree with that of the associated relay WA the apparatus is set into operation to indicate at the dispatcher's office in succession, the condition of all of the track sections and all of the switches associated with the separate sections. In explaining this operation, I will first assume that a train enters section a—b at station 1. When this occurs, relay IR becomes de-energized. Back contact 57 of relay IR then closes to complete a circuit from terminal x¹, over back contact 51 of relay IR, wire 58, normal contact 59 of relay IRA, wires 60 and 61, back contact 45 of relay IV, wire 63, and winding of relay IP to terminal y¹. Relay IP becomes energized, and interrupts, at back contact 54 thereon, the circuit just traced for relay L at the office. When relay L becomes de-energized, the closing of back contact 19 of this relay completes the circuits already traced for relays T¹ and T² so that both of these relays become energized. The energization of relay T¹ sets the pole changer relay Q into operation as has already been described. Relay Q thereafter operates as long as relay T¹ remains energized. Furthermore, the closing of front contact 53 of relay T¹ disconnects line wire 17 from the relay L and connects this line wire with a wire 64. Relay OB at the office is de-energized and under these conditions the wire 64 is connected over back contact 65 of relay OB with a wire 66 which may be connected with apparatus on each of the control panels when the corresponding relay J is energized. The purpose of this arrangement will be explained hereinafter.

When relay T² becomes energized, the opening of back contact 22 extinguishes the pilot lamp 21, thereby informing the operator that the apparatus is functioning to indicate the condition of the apparatus located at the several stations. Furthermore, the closing of front contact 22 of relay T² connects terminal x⁰ with the polar armature 67 of relay Q, and the closing of front contact 15 of relay T² connects the polar armature 13 of relay Q directly with line wire 14. With contact

13 of relay Q occupying its left-hand position, current flows from terminal OZX of line battery OZ, over contact 13 of relay Q, wire 68, and front contact 15 of relay T², and thence over the uninterrupted line circuit comprising line wire 14, the polarized line relays D at each of the several stations in series, and the common return wire 18, back to battery OZ. When contact 13 is swung to the right, however, current flows from the midpoint of battery OZ, through line wire 18, to relay 10 ID, and thence through each of the other polarized line relays D in series and returns by way of line wire 14, front contact 15 of relay T², wire 68, and contact 13 of relay Q, to terminal OZY of battery OZ. It follows, therefore, that alternate operation of relay Q energizes relays D at all of the stations alternately in their normal and reverse directions in synchronism with relay Q.

The relay U associated with each relay D is a two-winding slow release relay which is arranged to be repeatedly energized when the associated relay D is being operated intermittently in response to the operation of the pole changer relay Q. Referring particularly to station 1, for example, when armature 69 of relay ID swings to the right, the lower winding of relay 1U is connected directly with terminals x¹ and y¹, and when the armature 69 is swung to the left, the upper winding of relay 1U is connected with terminals x¹ and y¹. Due to the slow releasing characteristics of relay 1U, however, the relay is maintained in its energized condition during alternate reversals of relay ID. When relay 1U is energized, back contact 49 is open to interrupt the circuit previously traced for relay IS. Current flows from terminal x¹, however, over back contact 75 of relay IM2, wire 76, front contact 77 of relay IS, wire 78, and winding of relay IS to terminal y¹. Relay IS is therefore stuck up as long as relay IM2 is de-energized. The closing of front contact 49 of relay 1U completes a circuit for relay IV which will be obvious from the drawings, thereby energizing this relay and opening back contact 62 thereon. As a result, relay IP is de-energized, thereby reconnecting line wire 17 with wire 55. It will be remembered that the line relay L at the office was de-energized by the opening of back contact 54 of relay IP. But the reclosing of contact 54 does not energize relay L, because the circuit for relay L is now open at back contact 53 of relay T¹ at the office.

It will be evident therefore that controls or indication may be transmitted over the wire 17 only as long as the slow acting relay 1U is held energized by the continued operation of the line relay ID. That feature of my invention which relates to the control of receiving apparatus by a slow acting relay in this manner is not claimed herein, but is disclosed and claimed in an application for a patent for an improvement in Railway traffic controlling apparatus, Serial No. 254,690, filed by me on the same date as the present application.

The first time that the armature 69 of relay ID swings to the right, current flows from terminal x¹ over contact 69 of relay ID, wires 70 and 71, front contact 72 of relay IS, wires 73, 83, and 74, and winding of relay IM1 to terminal y¹. Relay IM1 thereupon becomes energized and a stick circuit for this relay is then closed from wire 70, through wires 79 and 80, front contact 81 of relay IM1, wires 82 and 74, and winding of relay IM1 to terminal y¹. The relay IM1 having once been energized, then, is held in its energized condition as long as the armature 69 of relay ID

occupies its right-hand position. When relay **1M1** is energized, current flows from terminal x^1 , over contact **69** of relay **1D**, wires **70**, **79** and **80**, front contact **84** of relay **1M1**, wire **85**, and winding of relay **1J** to terminal y^1 . Relay **1J** then becomes energized to close front contacts **56** and **86**. It will be manifest from the drawings that line wire **16** is normally closed at station **1** over back contact **86** of relay **1J**. When this relay becomes energized, however, the line wire **16** is connected at station **1** with a terminal of line battery **1Z** over a circuit which passes from the line wire through front contact **86** of relay **1J**, wire **87**, back contact **88** of relay **1B**, wire **89**, winding of relay **15** **1RA**, wire **91**, and thence to one terminal or the other of battery **1Z** according as track relay **1R** is energized or de-energized.

As has already been explained, line wire **17** is normally closed through back contact **54** of relay **20** **1P**, and back contact **56** of relay **1J** at station **1**. It has further been explained that after the operation of relay **1D** has commenced, relay **1P** is de-energized. But relay **1J** is now energized and under these conditions line wire **17** is connected **25** at station **1** with a terminal of battery **1Z** over a circuit which may be traced from the line wire over back contact **54** of relay **1P**, wire **55**, front contact **56** of relay **1J**, wire **93**, back contact **92** of relay **1B**, wire **122**, winding of relay **1WA**, wire **30** **123**, and thence with one terminal or the other of line battery **1Z** according as switch **3** occupies its normal or reverse position to close contact **36**—**36^a** or **36**—**36^b**. It will be plain, therefore, that when relay **1J** is energized, line wire **16** is connected at **35** station **1** with positive or negative line battery according as track relay **1R** is energized or de-energized, respectively. Furthermore, when relay **1J** is energized, line wire **17** is connected at station **1**, with positive or negative line battery **40** according as switch **3** at this station occupies its normal or reverse position, respectively.

Returning now to a consideration of the apparatus located at the control office, when the armatures of relay **Q** first swing to their right-hand positions, current flows from terminal x^0 , over front contact **22** of relay **T²**, wires **124** and **125**, contact **67** of relay **Q**, wires **94** and **95**, back contact **96** of relay **OS**, wire **97**, and winding of relay **OM1** to terminal y^0 . Relay **OM1** therefore becomes energized and a stick circuit is then closed from wire **94**, over wires **100** and **126**, front contact **98** of relay **OM1**, wires **99** and **99^a**, and winding of relay **OM1** to terminal y^0 . Furthermore, current flows from **55** terminal x^0 , over front contact **22** of relay **T²**, wires **124** and **125**, contact **67** of relay **Q**, wires **94**, **100**, **101** and **102**, front contact **103** of relay **OM1**, wire **104**, and winding of a selector relay **OJ1**, to terminal y^0 . When relay **OJ1** becomes **60** energized, the closing of front contact **108** of this relay connects line wire **16** at the office with the common wire **18** over a circuit which may be traced from line wire **16** through back contact **105** of relay **OB**, wires **106** and **107**, front contact **108** of relay **OJ1**, wire **109**, winding of relay **1RK**, and wires **110** and **110^a** to common wire **18**. Since the common wire **18** is connected with the midpoint of line battery **1Z** at station **1**, it will be plain that when relay **OJ1** at the office **70** and relay **1J** at station **1** are energized, a message channel is completed from station **1** to the office over which relay **1RA** at the station and relay **1RK** at the office are energized in series by current of one polarity or the other, depending upon **75** the condition of energization of relay **1R**. I

have assumed that relay **1R** is now de-energized and under these conditions the polarity of the current supplied to relays **1RK** and **1RA** is such that these relays become energized in their reverse direction so that their contacts are swung to the left. The track relay **1R** thus not only transmits a message to the office of a character which indicates its position, but the character of the message is such as to cause relay **1RA** to be operated into agreement with the new position of relay **1R** so as to open at contact **59** that branch of the starting circuit which as already described was closed at contact **57** of relay **1R** to set the apparatus into operation. The closing of reverse contact **59** of relay **1RA** has no effect at this time, but the closing of reverse contact **114** of relay **1RK** connects an indicator lamp **116** with terminals x^0 and y^0 so that this lamp **116** becomes lighted to indicate to the operator the fact that a train now occupies track section **a**—**b** at station **1**.

With relay **OJ1** energized, front contact **112** of this relay is also closed and under these conditions, wire **66** at the office is connected through wire **111**, front contact **112** of relay **OJ1**, wire **113**, winding of relay **1WK** and wire **110** to common wire **18**. It has already been explained that wire **66** is now connected with line wire **17** and since common wire **18** is connected with the midpoint of line battery **1Z**, it follows that a second message channel is completed from station **1** to the office over which current of one relative polarity or the other is supplied to relays **1WA** and **1WK** in series, depending upon the position of switch **3** at station **1**. As shown in the drawings, the switch **3** occupies its normal position so that the positive terminal **1ZX** of line battery **1Z** is connected with wire **123** at station **1**, and under these conditions, relays **1WA** and **1WK** are energized in the normal direction. The impulse transmitted to the office to operate relay **1WK** thus operates **1WA** into agreement with switch **3** in case it does not already occupy such position. With relay **1WK** energized in the normal direction, current flows from terminal x^0 over normal contact **117** of relay **1WK**, wire **118**, lamp **119**, wire **121**, contact **127** of a manually operable lever **14** to terminal y^0 . Lamp **119** is therefore lighted to indicate to the operator that switch **3** at station **1** occupies its normal position. **50**

The impulses delivered to relays **1RK** and **1RA** and to relays **1WK** and **1WA** during the operations just described persist only during the brief interval that relays **1D** and **Q** occupy their right-hand positions. But relays **1RK** and **1WK** remain in the positions to which they were last moved so that after having once been lighted, lamps **116** and **119** remain lighted to indicate the condition of the apparatus until this condition is changed. **55**

When relay **Q** next operates to swing its armature **67** to the left, relay **OM2** becomes energized, current flowing from terminal x^0 , over front contact **22** of relay **T²**, wires **124** and **125**, contact **67** of relay **Q**, wires **129** and **130**, front contact **131** of relay **OM1**, wires **132** and **133**, and winding of relay **OM2** to terminal y^0 . As soon as relay **OM2** becomes energized, a stick circuit is closed for this relay from wire **129**, through wires **134** and **135**, front contact **136** of relay **OM2**, wires **137** and **133** and winding of relay **OM2** to terminal y^0 . It should be noted that relay **OM2** can become energized only if relay **OM1** has previously been energized, so that the apparatus affords a continuous check on the proper **70** **75** **80** **85** **90** **95** **100** **105** **110** **115** **120** **125** **130** **135** **140** **145** **150** **155** **160** **165** **170** **175** **180** **185** **190** **195** **200** **205** **210** **215** **220** **225** **230** **235** **240** **245** **250** **255** **260** **265** **270** **275** **280** **285** **290** **295** **300** **305** **310** **315** **320** **325** **330** **335** **340** **345** **350** **355** **360** **365** **370** **375** **380** **385** **390** **395** **400** **405** **410** **415** **420** **425** **430** **435** **440** **445** **450** **455** **460** **465** **470** **475** **480** **485** **490** **495** **500** **505** **510** **515** **520** **525** **530** **535** **540** **545** **550** **555** **560** **565** **570** **575** **580** **585** **590** **595** **600** **605** **610** **615** **620** **625** **630** **635** **640** **645** **650** **655** **660** **665** **670** **675** **680** **685** **690** **695** **700** **705** **710** **715** **720** **725** **730** **735** **740** **745** **750** **755** **760** **765** **770** **775** **780** **785** **790** **795** **800** **805** **810** **815** **820** **825** **830** **835** **840** **845** **850** **855** **860** **865** **870** **875** **880** **885** **890** **895** **900** **905** **910** **915** **920** **925** **930** **935** **940** **945** **950** **955** **960** **965** **970** **975** **980** **985** **990** **995** **1000** **1005** **1010** **1015** **1020** **1025** **1030** **1035** **1040** **1045** **1050** **1055** **1060** **1065** **1070** **1075** **1080** **1085** **1090** **1095** **1100** **1105** **1110** **1115** **1120** **1125** **1130** **1135** **1140** **1145** **1150** **1155** **1160** **1165** **1170** **1175** **1180** sequence of operations. When armature 67 of relay Q was swung to the left, the circuits for relays OM1 and OJ1 were both opened. Relay OJ1 immediately becomes de-energized, but relay OM1, due to its slow releasing characteristics, holds its front contacts closed for a brief interval of time sufficiently long to insure that relay OM2 becomes energized. When front contact 139 of relay OM2 closes, current flows from terminal x^0 , over front contact 22 of relay T², wires 124 and 125, contact 67 of relay Q, wires 129 and 130, back contact 131 of relay OM1, wire 138, front contact 139 of relay OM2, wire 140, and winding of relay OJ2 to terminal y^0 . It will be plain that this circuit can be completed only after relay OM1 has opened. When relay OJ2 becomes energized, the indication apparatus associated with panel number 2, (not shown in the drawings) is connected with wires 66 and 106, in the same manner as has already been described in connection with the operation of the apparatus on panel number 1 when relay OJ1 is energized.

Since the polarized line relays D located at the several stations operate in synchronism with relay Q, the armature of these line relays occupy their left-hand positions. As a result, relay M² associated with each such station is energized, each such relay being provided with a pick-up circuit including a front contact of the associated counting relay M¹ and a stick circuit including its own front contact. In similar manner, the counting relays M at the office and at each of the stations are energized successively in synchronism in response to operation of relay Q at the office. As each office counting relay becomes energized, a corresponding selector relay J at the office is energized to connect the apparatus on the associated panel with the line wires 17 and 16. Furthermore, the selector relay J located at each station is controlled by a proper one of the relays M at that station in the same manner that relay 1J is controlled by relay M¹ at station 1, so that as the counting relays at the several stations are energized in sequence, the apparatus at panel number 1 is first connected with the apparatus at station 1, the apparatus at panel number 2 is next connected with the apparatus at station number 2 and so on in succession until relays M¹ at office and at all of the stations are energized, whereupon relay 1J at station 1 is energized to connect the apparatus at this station with line wires 17 and 16. At the same time, the energization of relay OM1 at the office energizes the corresponding relay J associated with panel 1 (not shown in the drawings). It will be plain therefore that by thus successively operating the counting relays in synchronism, indications are received at the office from all of the stations in order.

When relay Q next becomes energized to swing its armatures to the left, relay OM8 becomes energized and the relays M⁸ at each of the stations also become energized. The energization of relay OM8 opens its back contact 20 and thus breaks the circuit for relay T¹, which relay thereupon becomes de-energized. The closing of back contact 9 of relay T¹ discontinues the operation of the relay Q and holds winding 6 of this relay energized so that the contacts of the relay remain in their left hand positions. At the same time, the closing of back contact 53 of relay T¹ connects line wire 17 with relay L, which relay becomes energized over the circuit hereinbefore traced for this relay, over back contact 50 of relay OP. Relay L therefore becomes closed, to

open back contact 19 and de-energize relay T². The opening of front contact 22 of relay T² disconnects battery from contact 67 of relay Q and consequently, de-energizes relay OM8. Furthermore, the closing of back contact 22 of relay T² lights lamp 21 to indicate that the apparatus has returned to its normal condition.

It should also be pointed out that when front contact 15 of relay T² opened, the circuit was interrupted for all of the relays D at the several stations, and these relays assume the positions shown in the drawings. The last relay M⁸ in each series of counting relays, therefore, becomes de-energized and all of the relays U become de-energized. The closing of a back contact of each relay U completes a pick-up circuit for the associated relay S. Referring particularly to station 1, the opening of front contact 49 of relay 1U de-energizes relay 1V and allows the back contact 62 of relay 1V to close. Relay 1P, however, does not become energized, because relay 1RA is now reversed and track relay 1R is de-energized. In similar manner, the apparatus located at each of the remaining stations is restored to its normal condition by the de-energization of relay U at such station and the consequent de-energization of relay V associated therewith.

With the apparatus thus far described, it will be apparent that when any change occurs in the condition of a track section or the position of a switch at any of the stations, this change results in the energization of the starting relay P at such station. The equipment is then set into operation and continues without interruption to transmit to the office an indication of the condition of the apparatus at each of the stations, at the conclusion of which function the entire system is returned to its normal condition preparatory to transmitting indications of other changes.

In addition to the function of indication, it is desirable to enable the operator to selectively change the positions of the switches or signals located adjacent the several stations. In explaining the operation of the apparatus for this purpose, I will first assume that the operator wishes to reverse switch 3 and to place the signals at stop at station 1. To accomplish this result, he moves lever 1¹ on panel number 1 to the left, thereby extinguishing lamp 119 and moving contact 128 to its left-hand position. He also moves lever 1¹ to its middle position. The operator then closes the master key r, so that current flows from terminal x^0 , through back contact 22 of relay T², wire 149, master key r, wire 150, and winding of relay OP to terminal y^0 . Relay OP therefore becomes energized and the master key r may then be released, relay OP remaining energized by virtue of a stick circuit which may be traced from terminal x^0 , through back contact 151 of relay OB, wire 152, front contact 153 of relay OP, and winding of relay OP to terminal y^0 . The opening of back contact 50 of relay OP interrupts the line circuit including relay L, whereupon this relay becomes effective to set the apparatus into operation in exactly the same manner as if relay L had been de-energized by opening line wire 11 at one of the stations for the purpose of transmitting a change of indication to the office. The relay Q therefore operates to energize in synchronism the relays M at the several stations and an indication is received from each of the stations in turn on the panels in the control office. The operation is precisely the same as has already been described

until relays M8 become energized and up to this point no further explanation is necessary.

At the office, relay OP is now energized and when relay OM8 picks up to break the back contact 20 of this relay, relay T¹ does not become de-energized, but remains closed because a branch is now completed around back contact 20 of relay OM8 over front contact 154 of relay OP.

The relay T¹ therefore remains in its energized condition and the relay Q continues to operate. When contact 67 of relay Q next swings to the right, current from terminal x⁰ flows over front contact 22 of relay T², wires 124 and 125, contact 67 of relay Q, wires 94, 100, 101 and 155, thence over front contact 156 of relay OM8, wires 157 and 99^a, and winding of relay OM1 to terminal y⁰. Relay OM1 therefore becomes energized and is subsequently stuck up over its own front contact 98 even after relay OM8 releases.

When relay OM2 became energized during the first cycle of operation of the counting relays a circuit was closed for relay OS from terminal x⁰, over front contact 141 of relay OM2, wires 142 and 143, and winding of relay OS.

This relay OS is subsequently stuck up over its own front contact 145 and front contact 22 of relay T². Under these conditions, when front contact 166 of relay OM1 becomes energized current flows from terminal x⁰, over front contact 22 of relay T², wires 124 and 125, contact 67 of relay Q, wires 94 and 95, front contact 96 of relay OS, wire 167, front contact 66 of relay OM1, wire 168, front contact 169 of relay OP, wire 170, and winding of relay OB to terminal y⁰.

This circuit is interrupted as soon as relay OM1 becomes de-energized but relay OB is subsequently maintained in its energized condition by virtue of a stick circuit which may be traced from terminal x⁰, over back contact 19 of the relay L, wire 171, front contact 172 of relay OB, and winding of relay OB to terminal y⁰.

When relay OM1 is energized, relay OJ1 becomes energized as was described hereinbefore but the energization of this relay now connects the line wires 16 and 17 with levers 1^d and

1^f instead of with the indicating relays 1RK and 1WK. For example, when front contact 158 of relay OJ1 closes, a circuit is completed from line wire 16 through front contact 105 of relay OB, wires 159 and 160, front contact 158 of relay OJ1, wire 161 and contact 128 of lever 1^d (now reversed) to terminal OZY of line battery OZ.

In similar manner, line wire 17 is connected through front contact 53 of relay T¹, wire 64, front contact 65 of relay OB, wires 162 and 163, front contact 164 of relay OJ1, and wire 165 to lever 1^f.

Since this lever is now in its middle position, the line wire 17 is now disconnected from battery.

At station 1, the relay 1D continues to operate after relay 1M8 has become energized and when the armature 69 of relay 1D next swings to the right, current flows from terminal x¹, over contact 69 of relay 1D, wires 70, 79, and 172 and thence over front contact 173 of relay 1M8, wires 174, 83 and 74, and winding of relay 1M1 to terminal y¹.

Relay 1M1 therefore becomes energized, even though relay 1S is now de-energized so that the pick-up circuit first traced for relay 1M1 is open.

As the operation of relay 1D continues, relays M at station 1 are energized in the same manner as described in connection with the transmission of indications from the stations to the office.

When relay 1M1 becomes energized, since relay 1S was de-energized when back contact 75 of relay 1M2 became open during the first cycle of

operation of the counting relays to break the stick circuit for relay 1S, current flows from terminal x¹, over back contact 175 of relay 1S, wire 176, front contact 177 of relay 1M1, wires 178 and 179, and winding of relay 1B to terminal y¹. Relay 1B therefore becomes energized and is subsequently maintained in its energized condition by virtue of a stick circuit which passes from terminal x¹, over front contact 49 of relay 1U, wires 180 and 181, front contact 182 of relay 1B, wires 183 and 179, and winding of relay 1B to terminal y¹. It should also be pointed out that the energization of relay 1M1 picks up relay 1J and with this relay energized, line wire 16 is connected through front contact 86 of relay 1J, wire 87, front contact 88 of relay 1B, wire 184, winding of relay 1W, and wire 185 to common wire 18, and thence to the midpoint of line battery OZ at the office.

From the foregoing explanation, it will be seen that when relay OJ1 at the office and relay 1J at station 1 are both energized, relay 1W is supplied with current of one polarity or the other over wires 16 and 18, according as lever 1^d occupies its normal or reverse position.

I have assumed that lever 1^d now occupies its left-hand or reverse position, and under these conditions the polarity of the current supplied to relay 1W is such that this relay becomes energized in the reverse direction, swinging its contacts to the left.

When this happens motor 1E is energized by current which flows from terminal x¹, over front contact 44 of relay 1R, wire 23, contact 24—24^a of circuit controller 1C, wire 25, reverse contact 26 of relay 1W, wire 27, armature 28 of motor 1E, wire 30, reverse contact 31 of relay 1W, wire 32,

and field 29 of motor 1E to terminal y¹. The motor 1E is therefore energized to drive switch 3 toward its reverse position. When the switch attains its full reverse position, contact 24—24^a opens, thereby de-energizing the motor. It

should be noted that when the switch reverses, contacts 35—35^b and 36—36^b are closed so that when next these contacts are connected with the line wires to indicate at the office the condition of the apparatus at the station 1, the relay 1WK will

become energized in its reverse direction to light lamp 120 and indicate that the switch 3 at station 1 is reversed. The operation of the apparatus in moving a switch from its reverse to its normal position will be understood without further explanation. It should also be pointed out that when relay 1J becomes energized, with relay 1B energized, line wire 17 is connected over back contact 54 of relay 1P, wire 55, front contact 56 of relay 1J, wire 93, front contact 92 of relay 1B, wire 186, winding of relay 1H, wire 187, winding of relay 1F and wire 188 with line wire 18, back

to the midpoint of line battery OZ at the office. It follows, therefore, that when relays OJ1, 1B, and 1J are energized, relays 1H and 1F are supplied in series with current of one polarity or the other over line wires 16 and 18, depending upon the position of lever 1^f on panel number 1 at the office. I have assumed, however, that lever 1^f occupies its middle position. Under these conditions, relays 1H and 1F are both de-energized.

When relay 1J becomes energized, however, a circuit is closed from terminal x¹, over front contact 89 of relay 1J, wire 190, front contact 191 of relay 1B, wire 192, back contact 193 of relay 1H, wire 194, lower winding of relay 1G to terminal y¹. Current flowing over this circuit energizes relay 1G in the reverse direction to open contact 40. Had relay 1H been energized,

motor 1E would have been de-energized and the switch 3 would have been moved to its normal position. The apparatus at the station 1 would then indicate that the switch 3 at station 1 is in its normal position. The operation of the apparatus in moving a switch from its reverse to its normal position will be understood without further explanation. It should also be pointed out that when relay 1J becomes energized, with relay 1B energized, line wire 17 is connected over back contact 54 of relay 1P, wire 55, front contact 56 of relay 1J, wire 93, front contact 92 of relay 1B, wire 186, winding of relay 1H, wire 187, winding of relay 1F and wire 188 with line wire 18, back

to the midpoint of line battery OZ at the office. It follows, therefore, that when relays OJ1, 1B, and 1J are energized, relays 1H and 1F are supplied in series with current of one polarity or the other over line wires 16 and 18, depending upon the position of lever 1^f on panel number 1 at the office. I have assumed, however, that lever 1^f occupies its middle position. Under these conditions, relays 1H and 1F are both de-energized.

When relay 1J becomes energized, however, a circuit is closed from terminal x¹, over front contact 89 of relay 1J, wire 190, front contact 191 of relay 1B, wire 192, back contact 193 of relay 1H, wire 194, lower winding of relay 1G to terminal y¹. Current flowing over this circuit energizes relay 1G in the reverse direction to open contact 40. Had relay 1H been energized,

motor 1E would have been de-energized and the switch 3 would have been moved to its normal position. The apparatus at the station 1 would then indicate that the switch 3 at station 1 is in its normal position. The operation of the apparatus in moving a switch from its reverse to its normal position will be understood without further explanation. It should also be pointed out that when relay 1J becomes energized, with relay 1B energized, line wire 17 is connected over back contact 54 of relay 1P, wire 55, front contact 56 of relay 1J, wire 93, front contact 92 of relay 1B, wire 186, winding of relay 1H, wire 187, winding of relay 1F and wire 188 with line wire 18, back

to the midpoint of line battery OZ at the office. It follows, therefore, that when relays OJ1, 1B, and 1J are energized, relays 1H and 1F are supplied in series with current of one polarity or the other over line wires 16 and 18, depending upon the position of lever 1^f on panel number 1 at the office. I have assumed, however, that lever 1^f occupies its middle position. Under these conditions, relays 1H and 1F are both de-energized.

When relay 1J becomes energized, however, a circuit is closed from terminal x¹, over front contact 89 of relay 1J, wire 190, front contact 191 of relay 1B, wire 192, back contact 193 of relay 1H, wire 194, lower winding of relay 1G to terminal y¹. Current flowing over this circuit energizes relay 1G in the reverse direction to open contact 40. Had relay 1H been energized,

motor 1E would have been de-energized and the switch 3 would have been moved to its normal position. The apparatus at the station 1 would then indicate that the switch 3 at station 1 is in its normal position. The operation of the apparatus in moving a switch from its reverse to its normal position will be understood without further explanation. It should also be pointed out that when relay 1J becomes energized, with relay 1B energized, line wire 17 is connected over back contact 54 of relay 1P, wire 55, front contact 56 of relay 1J, wire 93, front contact 92 of relay 1B, wire 186, winding of relay 1H, wire 187, winding of relay 1F and wire 188 with line wire 18, back

to the midpoint of line battery OZ at the office. It follows, therefore, that when relays OJ1, 1B, and 1J are energized, relays 1H and 1F are supplied in series with current of one polarity or the other over line wires 16 and 18, depending upon the position of lever 1^f on panel number 1 at the office. I have assumed, however, that lever 1^f occupies its middle position. Under these conditions, relays 1H and 1F are both de-energized.

When relay 1J becomes energized, however, a circuit is closed from terminal x¹, over front contact 89 of relay 1J, wire 190, front contact 191 of relay 1B, wire 192, back contact 193 of relay 1H, wire 194, lower winding of relay 1G to terminal y¹. Current flowing over this circuit energizes relay 1G in the reverse direction to open contact 40. Had relay 1H been energized,

motor 1E would have been de-energized and the switch 3 would have been moved to its normal position. The apparatus at the station 1 would then indicate that the switch 3 at station 1 is in its normal position. The operation of the apparatus in moving a switch from its reverse to its normal position will be understood without further explanation. It should also be pointed out that when relay 1J becomes energized, with relay 1B energized, line wire 17 is connected over back contact 54 of relay 1P, wire 55, front contact 56 of relay 1J, wire 93, front contact 92 of relay 1B, wire 186, winding of relay 1H, wire 187, winding of relay 1F and wire 188 with line wire 18, back

to the midpoint of line battery OZ at the office. It follows, therefore, that when relays OJ1, 1B, and 1J are energized, relays 1H and 1F are supplied in series with current of one polarity or the other over line wires 16 and 18, depending upon the position of lever 1^f on panel number 1 at the office. I have assumed, however, that lever 1^f occupies its middle position. Under these conditions, relays 1H and 1F are both de-energized.

current would have flowed over the circuit just traced, through front contact 193 of relay H and wire 195 through the upper winding of relay 1G to terminal y^1 , thereby energizing relay 1G in the normal direction and holding contact 40 closed.

The movement of traffic from left to right over the switch at each station is controlled by a signal designated by the reference character t with an exponent corresponding to the location. The movement of traffic in the opposite direction over each switch is governed by two signals u and v with exponents corresponding to the location. The upper blades of the signals t and their opposing signals v are main signals governing traffic movements over the main track with switch 3 normal, as shown, while the lower arms of the signals t and their opposing signals u are auxiliary signals for governing traffic movements into and out of the sidings. The signals u and v which govern the movement of traffic into the single track stretch to the left of switch 3 are commonly referred to as "starting signals" while the opposing signal t may be called a "leaving signal." Referring particularly to the apparatus located at station 1, the signals associated with switch 3 at this station are controlled jointly by relays 1G and 1F. As has already been explained, since lever 1^f at the control office occupies its middle position, contact 40 of relay 1G is now open. The operating circuits for all of the signals are therefore interrupted and the signals indicate stop. As shown in the drawings, however, relays 1G and 1F are both energized in the normal direction so that their armatures are swung to the right. Under these conditions current flows from terminal x^1 , over front contact 34 of relay 1R, wire 39, normal contact 40 of relay 1G, wire 41, normal contact 42 of relay 1F, wire 43, contact 38-38^a of the circuit controller 1C controlled by switch 3, wire 44, operating mechanism of the upper blade of signal t to terminal y^1 . This circuit is closed only when relays 1F and 1G are both energized in the normal direction as when lever 1^f occupies its right-hand position, and when switch 3 occupies its normal position. If the operator moves his lever 1^f to the left-hand position, relay 1F will be energized in the reverse direction when relays 1J and 1OJ become energized but since relay 1H becomes closed, relay 1G is energized in the normal direction, and current then flows from terminal x^1 , over front contact 34 of relay 1R, wire 39, normal contact 40 of relay 1G, wire 41, reverse contact 42 of relay 1F, wire 46, contact 37-37^a of circuit controller 1C, wire 47, operating mechanism of signal v^1 to terminal y^1 . When this circuit is closed, signal v^1 indicates proceed. In similar manner, if switch 3 is reversed, the lower blade of signal t^1 or signal u^1 is cleared, according as relay 1F is energized in the normal or reverse direction.

It should, of course, be pointed out that the levers 1^f and 1^d could be mechanically interlocked to prevent clearing a signal until the switch had been moved to an extreme position. Furthermore, the levers could be further interlocked to prevent movement of the lever 1^d to operate the switch until the lever 1^f had been placed in the middle position to set the signals at stop, but this mechanical interlocking is not essential to safety with the circuits arranged as shown.

In the foregoing description I have referred particularly to the apparatus associated with panel number 1 at the office and to the appa-

ratus located at station 1. It should be understood however, that each of the remaining panels at the office is provided with apparatus which operates in the same manner as has already been described in connection with panel number 1. Furthermore, the operation of the apparatus located at the remaining stations is similar in all respects to the operation of the apparatus located at station 1, with the single exception that since the relays J become energized in succession during the second cycle of operations of the counter relays, it follows that the switch control relays W and the signal control relays H, F and G at the several stations are successively placed under the control of the switch and signal levers located at the office.

At the office, when relay OM8 becomes energized, during this second cycle of operation of the counting relays, the opening of back contact 20 of this relay interrupts one circuit for relay T¹. The other circuit for this relay is now open at back contact 154 of relay OP, the latter relay being de-energized, because its stick circuit through back contact 151 of relay OB is now open, relay OB having been energized when relay OM1 became energized. The closing of relay OM8 therefore de-energizes relay T¹ and connects line relay L with line wire 17. If this line wire 17 is closed at all stations, that is, if all relays P and J at the several stations are de-energized, relay L becomes energized, thereby dropping T² and OB to restore the apparatus to its normal condition. If, however, the condition of the apparatus at any station has been changed, as would have been the case had switch 3 at station 1 been reversed in accordance with the preceding description, relay L would remain de-energized and the relay OM1 would again become energized to commence a third cycle of the operation of the counting relays at the office. During this third cycle of operation, indications would be received concerning the condition of the apparatus at the several stations, thereby registering any change in the condition of the switches or track circuits.

Returning now to the assumption that relay 1M8 at station 1 has been energized at the completion of the cycle of energization of relays M at this station, during which cycle control impulses were delivered to the several stations for governing the switch control relays and signal control relays; when relay 1D becomes de-energized due to the stopping of relay Q, relay 1U becomes de-energized, thereby de-energizing relay 1B and picking up relay 1S to restore the apparatus to the normal condition. The operation of the apparatus at each of the remaining stations is similar to that just described in connection with station 1.

To recapitulate the operation of the system, I will first assume that all parts are in the conditions in which they are illustrated in the drawings, and that a train moving toward the right enters track section a-b at station 1. Track relay 1R will open, thereby causing relay 1P to become energized, and this will interrupt the circuit for relay L at the dispatcher's office. The opening of relay L will close the circuits for relays T¹ and T². The closing of relay T¹ will set pole changer relay Q into operation, and will connect line wire 17 with wire 64 instead of with relay L. Relay T² will extinguish the pilot lamp 21, will connect line wire 14 with armature contact 13 of relay Q, and will connect contact 67 of this relay with battery terminal x⁰. Relay D at each station 1 to 7 will then be operated in

- unison with relay Q. Relay U at each station will close as soon as its associated D relay begins to operate, and will remain closed as long as such operation continues. The closing of each U relay will close the associated V relay, and this will open the associated P relay, but the opening of relay IP will not close relay L because the circuit for the latter will now be open at contact 53 of relay T¹.
- When armature 69 of relay ID swings to the right, relay IM1 will close, and this will energize relay IJ, which will serve to connect line wire 16 with battery terminal IZY through the back contact of track relay IR. Line wire 17 will now be connected with battery terminal IZX at station 1 through switch contact 36 and relay IWA.
- At the dispatcher's office, when the armature of relay Q swings to the right, it will close relay OM1, and this will close relay OJ1. With relay OJ1 at the office and relay IJ at station 1 both energized, relay IRA and relay IRK will be connected in series, and since relay IR is open, these polar relays will be energized in the reverse direction. The indicator lamp 116 will then become lighted to indicate that the track section at station 1 is occupied.
- The closing of relay OJ1 will also connect relays IWK and IWA in series, the polarity of the current supplied to them depending on the position of switch 3 at station 1, and since this switch is in normal position, lamp 119 will remain lighted to indicate this fact.
- When relay Q next swings its armature to the left, relay OM2 will become energized. Relays OM1 and OJ1 will now be open, and relay OJ2 will close. This will connect wires 16 and 17 with the apparatus on panel No. 2. Relay M2 at each station will now close, and each relay M1 will open. At station 2 (not shown) relay J will become closed due to the closing of its associated relay M², and so relays RK and WK on panel No. 2 will become energized to indicate the conditions of the track circuit and switch at station 3. As the operation of relay Q continues, the panel relays OJ will be successively closed, and the stations will be successively connected with the panels, until relays OM8, IM8, etc., become closed. The closing of relay OM8 will cause relay T¹ to open, and this will stop the operation of relay Q and will close relay L which in turn will cause relay T² to open. The opening of relay T² will cause relay OM8 to open, and it will also open the circuit for the D relays. All of the M8 relays will then open, the U relays open, the S relays will close, and the V relay will open, so that the indicating apparatus will be restored to its normal condition.
- Assuming now that the operator wishes to reverse switch 3 at station 1, he will reverse lever 60 I^d, move lever I^f to the middle position, and close the master key r. The closing of the master key will cause relay OP to become energized, and this will open the circuit for relay L, so that the apparatus will be set into operation to successively energize the M relays at the office and at all the stations. These counting relays will go through a complete cycle of operations, but when the cycle is completed the relay T¹ at the office will remain closed due to its stick circuit through contact 154 of relay OP, and so the counting relays will begin a second cycle. During the first cycle, when relay OM2 became closed, it caused relay OS to close, so that when relay OM1 closes during the second cycle it will cause relay OB to 76 become closed. Relay OJ1 will become closed at

the same time, but since relay OB is closed, line wires 16 and 17 will now be connected with lever contact 128 and lever I^f respectively instead of with the indication relays IRK and IWK. At station 1, when relay IM1 closes during the second cycle, relay IB will close and remain closed, and relay IJ will also close. A circuit is then closed including contact 128 in the office panel, line wire 16, relay IW at station 1, and line wire 18; and since contact 128 is reversed, relay 10 IW will reverse and so will cause switch 3 at station 1 to reverse. With relays IJ and IB both closed, and relay IH open, the lower winding of relay IG will be energized to open contact 40 and so to place the lower arm of signal t¹ at stop before the switch reverses. If the operator leaves contact I^f in the normal position, relay IH will be energized to cause the upper winding of relay IG to be energized and so to close contact 40, while relay IF will be energized in the normal direction. When the switch 3 reverses, then, the lower arm of signal t¹ will be cleared. If the operator reverses contact I^f, relay IF will be energized in the reverse direction so that when switch 3 reverses, signal u¹ will be cleared. 15

When relay OM8 at the office becomes closed at the end of the second cycle of operations, it will cause relays T¹ and T² to open, and this will result in all parts of the apparatus being restored to normal condition except of course that switch 30 3 at station 1 will be reversed.

In conclusion it should be mentioned that with apparatus embodying my invention, I have provided means for controlling apparatus located at a plurality of spaced stations, from a control 35 office over four line wires, and for receiving at the office indications of the condition of the apparatus located at such stations over the same four line wires. Furthermore, I accomplish these results by means of several chains of counting 40 relays, one chain located at the dispatcher's office and one chain located at each station, the several relays of all said chains being successively energized in synchronism to afford a continuous 45 check on the proper and accurate operation of the apparatus at all stages in its cycle.

Although I have herein shown and described only one form of railway traffic controlling apparatus embodying my invention, it is understood that various changes and modifications may be 50 made therein within the scope of the appended claims without departing from the spirit and scope of my invention.

Having thus described my invention, what I 55 claim is:

1. Railway traffic controlling apparatus comprising a plurality of traffic governing devices located at intervals along the trackway, a plurality of polarized relays one adjacent each such device, a normally open circuit including all such polarized relays in series, a plurality of indication relays one for each device all located at a control point and each responsive to the character of the current supplied thereto, a pair of line wires, means set into operation when the condition of any of said devices is changed for supplying said circuit with a predetermined number of energy impulses of alternately reversed polarity to operate said polarized relays in unison, means for successively connecting said indication relays 60 with said line wires for a brief interval of time, and means controlled by each said polarized relay and effective during the interval that the associated indication relay is connected with said line wires to supply the line wires with an im- 65

pulse of energy the character of which depends upon the condition of the device.

2. Railway traffic controlling apparatus comprising a plurality of traffic governing devices located at intervals along the trackway, a plurality of polarized control relays one for each device, means governed by each control relay for moving the associated device to one or the other of two positions according as such control relay is energized in one direction or the other, a plurality of polarized line relays one associated with each device, a plurality of manually operable levers all located at a control point, a manually operable master key, means set into operation when said master key is operated for supplying said line relays in series with a predetermined number of impulses of energy of alternately reversed polarity, a pair of line wires, means controlled by said line relays for connecting said control relays with said line wires for a brief interval of time in a predetermined sequence, and means located at said control point for supplying said line wires during each such interval with an impulse of energy of one polarity or the other depending upon the position of the lever associated with the control relay then connected with the line wires.

3. Railway traffic controlling apparatus comprising a polarized pole changer relay, manually operable means for setting said pole changer relay into operation, a series of counting relays, means responsive to operation of said pole changer relay to energize said counting relays in succession in such manner that each relay opens after the succeeding relay in the series becomes energized, means controlled by the last relay in said series for stopping said pole changer relay, a group of selector relays one for each relay except the last in said series, a circuit for the first selector relay in said group including a front contact of the first counting relay in said series, a circuit for each remaining selector relay in said group including a front contact of the associated counting relay and a back contact of the preceding counting relay, a pair of line wires, a plurality of manually operable levers one associated with each selector relay in said group, means effective when any selector relay in said group is energized to supply said line wires with an energy impulse of one polarity or the other according to the position of the associated lever, a plurality of other selector relays located at spaced points, means responsive to operation of said pole changer relay for energizing said other selector relays in a predetermined order, a polarized control relay associated with each of said other selector relays, means for connecting each control relay with said line wires when the associated selector relay is energized, and a plurality of traffic governing devices one controlled by each said control relay.

4. Railway traffic controlling apparatus comprising a polarized pole changer relay, manually operable means for setting said pole changer relay into operation, a series of counting relays, means responsive to operation of said pole changer relay to energize said counting relays in succession in such manner that each relay opens after the succeeding relay in the series becomes energized, means controlled by the last relay in said series for stopping said pole changer relay, a group of selector relays one for each counting relay except the last in said series, a circuit for the first selector relay in said group including a front contact of the first counting relay in said series, a circuit for each remaining selector relay

in said group including a front contact of the associated counting relay and a back contact of the preceding counting relay, and a plurality of spaced traffic governing devices selectively controlled by said selector relays.

5. In combination with an office and a plurality of stations, a line relay at each station, a normally open line circuit extending from the office to each station and including all said line relays, apparatus operating when actuated to close said line circuit and deliver to said line circuit a series of current impulses for operating said line relays, a chain of relays at the office operated in succession by said apparatus, other chains of relays one at each station, means controlled by each line relay for operating the relays of the associated chain successively and in synchronism with the chain at the office, and means for actuating said apparatus from the office or from any station.

6. In combination with an office and a plurality of stations, a first series of contacts at the office, additional series of contacts at each station, a normally closed line circuit extending from the office to each station, means effective when said line circuit is opened to operate the contacts of all said series successively and in synchronism means at the office and at each station for opening said line circuit, a plurality of movable devices associated with said first series, a plurality of series of electroresponsive devices one such series associated with each additional series of contacts, a second line circuit extending from said office to each station, means for supplying current of a selected character to said second line circuit under the control of a particular one of said movable devices when the corresponding contact of said first series is operated, and means for connecting a particular one of said electroresponsive devices with said second line circuit when the corresponding contact of the associated series is operated, the electroresponsive devices being so associated with the additional series of contacts that one only of such electroresponsive devices can be connected with said second line circuit at any one time.

7. In combination with an office and a plurality of stations, a first series of contacts at the office, an additional series of contacts at each station, a normally closed line circuit extending from the office to each station, means effective when said line circuit is opened to operate the contacts of all said series successively and in synchronism, means at the office and at each station for opening said line circuit, a plurality of electroresponsive devices one associated with each contact of said first series, a plurality of movable devices at least one located at each station, a second line circuit extending from said office to each station, means operating when any contact of said first series is operated for connecting a selected one of said electroresponsive devices with said second line circuit, and means controlled by the additional series of contacts at each station for supplying said second line circuit with current under the control of a selected one of said movable devices when a corresponding one of said electroresponsive devices is connected with said second line circuit.

8. In combination with an office comprising a relay L, and a plurality of stations each having a movable device 36, a relay WA normally coinciding with the position of the corresponding device, and a relay P, a normally closed line circuit extending from the office to each station and in-

- cluding relay L and the back contact of a relay P at each station, means operating when any device 36 moves out of agreement with the corresponding relay WA to energize the adjacent relay P, stepping means at each station operated in sequence following the opening of said line circuit, apparatus at each station effective while such stepping means is operating to deenergize the associated relay P, indicating means controlled by the stepping means at each station for delivering to the office from each station in order through the associated relay WA an impulse which operates such relay WA into agreement with the corresponding device 36, and means for again closing said line circuit after the operation of the last stepping means provided all relays WA correspond to the associated devices 36.
9. In combination with a chain of counting relays, two conductors, a source of energy having one terminal connected with one terminal of each of said relays, means for connecting the free terminal of said source with said two conductors alternately, means for at times connecting the remaining terminal of the first relay in said series with one of said conductors, means for connecting the free terminals of succeeding relays alternately with said conductors each over a front contact of the preceding relay in said chain, and means effective when any relay is energized for connecting its said remaining terminal with the conductor from which energy was supplied to pick up the relay.
10. In combination with an office and a station, two chains of counting relays one at the office and one at the station, an additional relay at the office, a second relay, means controlled from the office or the station for controlling said second relay, means controlled by said second relay for energizing said additional relay, apparatus effective when said additional relay is energized to operate the relays of said counting chains successively and in synchronism, and means controlled by the last relay of the office counting chain for deenergizing said additional relay.
11. In combination with an office and a plurality of stations, a chain of counting relays at the office and at each station, a starting relay at the office, means for controlling said starting relay from any station, an additional relay at the office having a pick-up circuit controlled by said starting relay, a stick circuit for said additional relay controlled by the last relay of the office counting chain, and means controlled by said additional relay for operating the relays of said counting chains successively and in synchronism.
12. In combination with an office and a plurality of stations, a line wire extending from said office through all said stations, a starting relay normally controlled over said line wire and arranged to be operated from any station, means effective when said starting relay is operated to disconnect said starting relay from said line wire and to transmit signals over said line wire between said office and said stations successively.
13. In combination, an office and a station connected by a line circuit, a normally open contact in said circuit at the office, a line relay in said circuit at the station, means controlled from said station for at times closing said normally open contact and for subsequently supplying current intermittently to said line circuit, and stepping means at said station operated

progressively in response to intermittent operation of said line relay.

14. In combination with an office and a plurality of stations connected by a line circuit, a normally open contact in said line circuit at the office, a plurality of line relays one at each station and all included in series in said line circuit, means controlled from any station for at times closing said normally open contact, transmitting means effective when said contact is closed for supplying said line circuit intermittently with current, stepping means at the office operated progressively by said transmitting means, stepping means at each station operated by the associated line relay in synchronism with the office stepping means, and means controlled by said stepping means for communicating between said office and said stations.

15. In combination with an office and a plurality of stations connected by a line circuit, a normally open contact in said line circuit at the office, a plurality of line relays one at each station and all included in series in said line circuit, means controlled from the office or from any station for at times closing said contact, means operating when said contact is closed to supply said line circuit with a series of current impulses for operating all said line relays in synchronism, and means effective upon the conclusion of said series of impulses for again opening said contact.

16. In a train dispatching system of the synchronous selector type; the combination with a selector system including a message channel rendered available momentarily once during each cycle of operation of such system, a dispatcher's office at one end of said message channel and a way station at the other end of said message channel, a lever at the dispatcher's office, indicating means at the dispatcher's office, electro-responsive control means at said way station, means for controlling said electro-responsive means in response to a change of the position of said lever and over said message channel, and means for controlling said indicating means responsive to the continuity of said message channel during the time said message channel is available for use.

17. In a train dispatching system of the synchronous selector type; the combination with a selector system including a message channel rendered available momentarily once during each cycle of operation of such system, a dispatcher's office at one end of said message channel and a way station at the other end of said message channel, a lever at the dispatcher's office, indicating means at the dispatcher's office, electro-responsive control means at said way station, means for controlling said electro-responsive means in response to a change of the position of said lever and over said message channel, and means for controlling said indicating means including a relay of the snap-action type included in said message channel.

18. In a train dispatching system of the synchronous selector wayside signal control type, the combination with a dispatcher's office and a plurality of way stations along the railway track, of a master synchronous selector at the dispatcher's office, a wayside synchronous selector distributed along the railway track, stepping means for operating said synchronous selectors in synchronism to successively complete a large number of message circuits, there being only one track indication message circuit and at least one

control message circuit for each way station, said stepping means including means for at times setting up successively said indication message circuits only and at other times setting up said indication message circuits and said control message circuits sequentially.

19. In a train dispatching system of the synchronous selector wayside signal control type, the combination with a dispatcher's office and a plurality of way stations along the railway track, of a master synchronous selector at the dispatcher's office, a wayside synchronous selector distributed along the railway track, stepping means for operating said synchronous selectors in synchronism to successively complete a large number of message circuits, there being only one track indication message circuit and at least one control message circuit for each way station, said stepping means including means for at times omitting some of said control circuits but not omitting any of said indication message circuits.

20. A synchronous selector of the counting relay type comprising; a line relay; a plurality of channel selecting relays arranged in order; a pick-up circuit for each odd numbered channel selecting relay including a front contact of the next preceding channel selecting relay, and a contact of said line relay closed when it assumes one extreme position; a pick-up circuit for each even numbered channel selecting relay including a front contact of the next preceding channel selecting relay, and a contact of said line relay closed when it assumes the other extreme position; and a stick circuit for each channel selecting relay including its own front contact and a contact opened upon the next change in the position of said line relay.

21. A synchronous selector of the counting relay type comprising; a polar line relay; a plurality of channel selecting relays arranged in order; a pick-up circuit for each odd numbered channel selecting relay including a front contact of the next preceding channel selecting relay and a contact of said line relay closed when it assumes one polar position; a pick-up circuit for each even numbered channel selecting relay including a front contact of the next preceding channel selecting relay and a contact of said line relay closed when it assumes the other polar position; and a stick circuit for each channel selecting relay including its own front contact and a contact opened upon the next change in the position of said line relay.

22. In a synchronous selector train dispatching system, the combination with a bank of neutral channel selecting relays in a dispatcher's office, another neutral bank of channel selecting relays at a way station, of a stepping circuit including a line relay at said way station, an office relay operating in synchronism with said line relay, an organization of circuits and contacts of said relays at said dispatcher's office and at said way station for causing simultaneous energization of the first relay of the neutral bank at said dispatcher's office and at the first relay of the neutral bank of relays at said way station when said line relay is energized by current of one polarity, and for causing simultaneous energization of the second relay of said dispatcher's office neutral bank and the second relay of the way station neutral bank when said line relay is energized by current of the reverse polarity, and a plurality of channel circuits each including the same line wire and contacts of corresponding chan-

nel selecting relays of the dispatcher's relay bank and said way station relay bank.

23. In a centralized traffic controlling system, the combination with one circuit for transmitting impulses from a control office to a plurality of way stations, of a message wire connecting said office and said way stations, a particular message circuit including said message wire, a two-position relay energized to be operated to a particular position during a particular impulse in a cycle applied to said one circuit providing a contact in said particular message circuit is closed, and means for operating said relay to the opposite position just prior to the control of said relay by said contact, whereby said relay assumes one position substantially continuously if said contact is closed and assumes the opposite position continuously if said contact is open.

24. In a centralized traffic controlling system, the combination with a message wire connecting two stations, selector means located partly at each said station and operable through a cycle of operation at a particular point in which a message circuit is closed including a contact at one said station, a two-position relay located at the other said station and arranged to be operated to a particular position upon closure of said circuit, and other means for operating said relay to its opposite position at a point in such cycle just preceding said particular point, whereby said relay substantially continuously assumes a position corresponding to whether said contact is open or closed.

25. In a centralized traffic controlling system, the combination with a message wire connecting two stations, selector means located partly at each station and operable through a cycle of operation at a particular point in which a message circuit is closed including a contact located at one station and a source of current, a two-position relay located at the other station and arranged to be operated to a particular position upon closure of said circuit, and other means for operating said relay to its opposite position.

26. In a centralized traffic controlling system, the combination with a message wire connecting two stations, selector means located partly at each said station and operable through a cycle of operation at a particular point in which a message circuit is closed including a contact at one said station, a two-position relay located at the other said station and arranged to be operated to a particular position upon closure of said circuit, and other means for operating said relay to its opposite position at a point in such cycle just preceding said particular point whereby said relay substantially continuously assumes a position corresponding to whether said contact is open or closed.

27. In a centralized traffic controlling system, the combination with a message wire connecting two stations, selector means located partly at each said station and operable through a cycle of operation at a particular point in which a message circuit is closed including a contact at one said station, a two-position relay located at the other station and arranged to be operated to a particular position upon closure of said circuit, and other means for operating said relay to its opposite position.

28. In a centralized traffic controlling system, the combination with a message wire connecting two stations, selector means located partly at each said station and operable through a cycle of operation at a particular point in which a

- message circuit is closed including a contact at one said station, a two-position relay located at the other station and arranged to be operated to a particular position upon closure of said circuit, and means including a local source of current at said other station for invariably moving said relay to its opposite position just prior to the point in said cycle when said relay is governed by said contact.
- 10 29. A centralized traffic controlling system comprising two stations connected by a line circuit, a contact located at one station, a two-position relay located at the other station, selector means located partly at each station and operable over said line circuit through a cycle of operation at a particular point in which said relay is moved to a particular position, and other means for subsequently operating said relay to its opposite position provided said contact is closed.
- 15 30. Means for substantially continuously indicating whether or not a contact is closed located at the remote end of an intermittently rendered available circuit, comprising a two-position relay, means for operating said relay to a particular position each time said circuit is rendered available and said contact is closed, and other means for operating said relay to the opposite position an instant before such relay is governed by said contact.
- 20 31. Means for substantially continuously indicating whether or not a contact is closed located at the remote end of an intermittently rendered available circuit, comprising a two-position relay, means for operating said relay to a particular position each time said circuit is rendered available and said contact is closed, and other means for operating said relay to the opposite position just before such relay is governed by said contact.
- 25 32. Means for substantially continuously indicating whether or not a contact is closed located at the remote end of an intermittently rendered available circuit comprising, a two-position relay and a source of current at the local end of said circuit for operating said relay to a particular position each time said circuit is rendered available and said contact is closed, and other means for operating said relay to the opposite position just before such relay is governed by said contact.
- 30 33. In combination with a railway track switch, two main signals for governing traffic in opposite directions over said switch in one position, two auxiliary signals for governing traffic in opposite directions over said switch in the other position, a first stick relay having an armature and two fixed contacts, a first circuit controller responsive to the position of said switch for connecting one contact of said stick relay with the main signal or the auxiliary signal governing traffic in one direction, a second circuit controller responsive to the position of said switch for connecting the other contact of said stick relay with the main signal or the auxiliary signal governing traffic in the opposite direction, a second stick relay for selectively supplying current to the armature of said first stick relay, means for controlling said first and second stick relays from a remote point, and means for controlling each said signal by traffic conditions in advance of such signal.
- 35 34. In combination with a stretch of railway track, two signals for governing traffic in opposite directions through said stretch, a first stick relay having an armature and two contacts, means for connecting said two contacts with said two signals respectively, a second stick relay for selectively supplying current to the armature of

said first stick relay, and means controlled from a remote point for independently controlling said first and second stick relays.

35. In a synchronous selector system comprising a central office and a plurality of way stations connected by a normally open line circuit, a master synchronous selector at said office including a series of contacts closed in sequence and a pair of line contacts closed alternately, a synchronous selector at each of said stations including a centrally biased three position polar line relay and a series of contacts closed in sequence by said relay when energized by consecutive impulses of alternating polarity, and means controllable from said office or from any station for closing said line and for setting said master selector into operation to impress impulses of alternating polarity on said line, whereby said office selector contacts are closed in sequence and in synchronism with corresponding station selector contacts at each station.

36. A synchronous selector comprising a control office and a plurality of way stations connected by a normally open line circuit, a master synchronous selector at said office including a series of contacts adapted to be closed in sequence and a line pole changer, a synchronous selector at each of said stations including a centrally biased three position polar line relay and a series of contacts adapted to be closed in sequence by said relay when energized by consecutive impulses of selected polarity, means controllable from said office or from any station for connecting said pole changer to said line and for energizing it repeatedly to transmit to said line a series of impulses each of selected polarity to actuate all of said selectors in synchronism, and means effective when the last contact of said series is operated and controlled by the office selector to deenergize said pole changer and to disconnect said pole changer from the line.

37. In combination with a line circuit, a selector of the relay chain type comprising a polar relay and a series of counting relays, means for energizing each counting relay in turn when said line circuit is repeatedly energized comprising a circuit for the first counting relay including a contact closed when said polar relay occupies a first position, a circuit for each even numbered counting relay closed when said polar relay occupies a second position and including a front contact of the next preceding odd numbered counting relay, a circuit for each succeeding odd numbered counting relay including the first named contact of said polar relay and a front contact of the next preceding even numbered relay, and means for repeatedly actuating said polar relay contact between said two positions in response to repeated energization of said line circuit.

38. A railway traffic indicating system comprising a control office and a remote station connected by a first and a second line circuit, a synchronous selector at said station adapted to be controlled from the office over said first line circuit, a second synchronous selector at the office adapted to be operated in synchronism with said station selector, a plurality of devices at said station, means responsive to a change in position of any station device and controlled over said second line circuit to set said synchronous selectors into operation, and means controlled by said synchronous selectors over said second line circuit to indicate the condition of each of said station devices at said office.

39. A centralized traffic controlling system for railroads comprising a control office and a plurality of stations, a stepping line circuit and a message line circuit extending from said office to each of said stations, a plurality of mechanisms at each station, a starting relay at the office, means at each station for actuating the starting relay over the message line circuit in response to a change in condition of any of the mechanisms at said station, a polarized line relay at each station included in said stepping line circuit, means operating when said starting relay is actuated to supply said stepping line circuit with a series of impulses each operating said line relays in unison to one position or the other, and means controlled over the message line circuit by said line relays for indicating at said office the changed condition of any of said mechanisms.
40. A centralized traffic controlling system for railroads comprising a control office and a plurality of stations, a stepping line circuit and a message line circuit extending from said office to each of said stations, a plurality of mechanisms one at each station, a starting relay at the office, means operating over said message line circuit in response to a change in the condition of any said mechanism for actuating said starting relay, a polarized line relay at each station included in said stepping line circuit, means operating when said starting relay is actuated to supply said stepping line circuit with a series of impulses each operating said line relays in unison to one position or the other, and means controlled over the message line circuit by said line relays for indicating at said office the conditions of all of said mechanisms in order.
41. Control means for controlling a starting signal governing the entrance of traffic into a single track section and controlling a leaving signal governing the movement of traffic out of such single track section comprising, a double throw contactor cooperating with two stationary contacts connected respectively with said starting signal and with said leaving signal, a second contactor for applying energy to said double throw contactor, and means for independently controlling said contactors from a remote point.
42. In combination, a track switch connecting the end of a passing siding to a single track section, two starting signals and two entering signals governing respectively the movement of traffic into and out of said single track section, a starting signal branch circuit, an entering signal branch circuit, a double throw contactor controlled in accordance with the position of said track switch for connecting said starting signal branch circuit to one or the other of said starting signals, a second double throw contactor controlled in accordance with the position of said track switch for connecting said entering signal branch circuit to one or the other of said entering signals, a third double throw contactor for applying electrical energy to one or the other of said two branch circuits, and a fourth contactor for cutting energy off said third contact and controlled from a remote point.
43. In combination, a track switch connecting the end of a passing siding to a single track section, two starting signals, two entering signals governing respectively the movement of traffic into and out of said single track section, a starting signal branch circuit, an entering signal branch circuit, a double throw contactor controlled in accordance with the position of said
- track switch for connecting said starting signal branch circuit to one or the other of said starting signals, a second double throw contactor controlled in accordance with the position of said track switch for connecting said entering signal branch circuit to one or the other of said entering signals, a third double throw contactor for applying electrical energy to one or the other of said two branch circuits, a fourth contactor for cutting off said electrical energy, a fifth contactor for controlling said track switch to either of its two extreme positions; selector means for controlling said third, said fourth and said fifth contactor from a remote point; and means for further controlling the particular signal selected in accordance with traffic conditions ahead of such signal.
44. In combination with an office and a plurality of stations, a line relay at each station, a normally open line circuit extending from the office to each station and including all said line relays, a normally closed line circuit extending from said office to each of said stations, apparatus operating when said normally closed line circuit is opened to close said normally open line circuit and deliver to such line circuit a series of current impulses for operating said line relays, a first chain of relays at the office operated in succession by said apparatus, other chains of relays one at each station, means controlled by each line relay for operating the relays of the associated chain successively and in synchronism with said first chain, and means at each station for opening said normally closed line circuit.
45. In combination with an office and a plurality of stations, a line relay at each station, a normally open line circuit extending from the office to each station and including all said line relays, a normally closed line circuit extending from said office to each of said stations, and including a relay L at the office, apparatus at the office operating when relay L becomes deenergized to close said normally open line circuit and deliver thereto a series of current impulses for operating said line relays, a first chain of relays at the office operated in succession by said apparatus, other chains of relays one at each station, means controlled by each line relay for operating the relays of the associated chain successively and in synchronism with said first chain, and means at each station for opening said normally closed line circuit.
46. A centralized traffic controlling system for railroads comprising an office and a plurality of field stations, a starting device at the office, means at the office and at each station for operating said starting device, a series of contacts at each of said stations, means controlled by said starting device for synchronously operating the contacts of all of said series through two complete cycles, a transfer relay at each station, means for energizing each said transfer relay during the second but not the first cycle of operation of said contacts, two sets of apparatus at each station, and means controlled by each said transfer relay for placing one set of apparatus at the corresponding station under the control of the associated contacts during the first cycle of operation and for placing the other set of apparatus at such station under the control of the associated contacts during the second cycle of operation.
47. A centralized traffic controlling system for railroads comprising an office and a plurality of field stations, a starting device at the office,

means at the office and at each station for operating said starting device, a chain of counting relays at each of said stations, means controlled by said starting device for synchronously operating the relays of all of said chains through two complete cycles, a transfer relay at each station, means for energizing each said transfer relay during the second but not the first cycle of operation of said chains, two sets of apparatus at each station, and means controlled by each said transfer relay for placing one set of apparatus at the corresponding station under the control of the associated counting relays during the first cycle of said chains and for placing the other set of apparatus at such station under the control of the associated counting relays during the second cycle of such chains.

48. In combination with an office and a station connected by a line circuit, a polarized line relay at the station included in said line circuit, means at the office for at times supplying said line circuit intermittently with current impulses of selected polarity, a slow acting relay arranged to be energized when said line relay is energized in either direction, stepping means at the office, and means effective if and only if said slow acting relay is energized to advance said stepping means progressively in response to periodic operations of said line relay.

49. In combination with an office and a station connected by a normally open line circuit, a polarized line relay at the station included in said line circuit, a slow-acting relay arranged to be energized when said line relay is energized in either direction but to be deenergized when said line relay is deenergized, means at the office for at times closing said line circuit and supplying the circuit intermittently with current impulses of selected polarity, stepping means at the station, and means effective when said slow acting relay is energized for operating said stepping means progressively in response to repeated operations of said line relay.

50. In a synchronous selector system comprising a central office and a plurality of way stations connected by a line circuit, a centrally biased three position polar line relay included in series in said line circuit at each station, a starting relay at the office, means for operating said starting relay from the office or from any station, a pair of stepping windings at said office, means effective when said starting relay is operated for energizing said stepping windings alternately, a synchronous selector at the office and at each station, means responsive to alternate energization of said stepping windings for actuating said office selector in step by step fashion and for delivering to said line circuit a series of impulses of alternately opposite polarity, and means at each station responsive to said series of impulses to operate the selector at such station in synchronism with the selector at the office.

51. The combination, with a control relay and means for operating such control relay repeatedly, of means for closing a series of contacts consecutively in response to such repeated operation of the control relay comprising a series of similar counting relays each having a release period greater than its pickup period less than the interval between consecutive operations of the control relay, a pickup circuit for each counting relay controlled by the control relay and by the preceding counting relay in said series, and a holding circuit for each counting relay including a contact of the control relay, whereby if any one

counting relay is deenergized and the next succeeding counting relay is energized, such next relay will pick up before such one relay releases.

52. A selector of the counting relay type comprising a line relay having a pair of contacts connected with a source of energy and adapted to be closed alternately, a plurality of counting relays arranged in order; a circuit for each odd numbered counting relay except the first including the winding of said relay and, in multiple, a front contact of said relay and a front contact of the next preceding counting relay, and in series therewith a contact of said line relay closed when such line relay assumes one position and said source of energy; a circuit for each even numbered counting relay including the winding of said relay and, in multiple, a front contact of said relay and a front contact of the next preceding counting relay and in series therewith a contact of said line relay closed when such line relay assumes another position and said source of energy; whereby each counting relay in turn is energized and deenergized; and means associated with each counting relay for holding it picked up until the next counting relay is picked up.

53. A selector of the counting relay type comprising a line relay and a series of counting relays, a pickup circuit for the first counting relay including a contact of the line relay and a contact of an auxiliary relay for picking up said first counting relay only during the first operation of the line relay, a pickup circuit for each remaining counting relay including a contact of the line relay and a contact of the next preceding counting relay but not including a contact of said auxiliary relay, a source of energy, means for operating said line relay to connect said source of energy successively to said pickup circuits to energize each of said counting relays in turn, and means for holding each counting relay picked up until the next succeeding counting relay picks up but for releasing it before the second succeeding counting relay picks up, whereby no two even numbered counting relays nor any two odd numbered counting relays are energized at the same time.

54. A selector of the counting relay type comprising a line relay, a plurality of counting relays arranged in a closed chain for operation consecutively through repeated cycles, and operating circuits for said counting relays including a pickup circuit for the first counting relay closed by the first only of a series of operations of the line relay, a pickup circuit for each remaining counting relay each controlled by the line relay and by the preceding counting relay, a second pickup circuit for the first counting relay controlled by the line relay and by a front contact of the last counting relay in the series, and means associated with each counting relay for holding such relay picked up until the next succeeding relay is picked up by the next operation of the line relay.

55. A centralized traffic controlling system for railroads comprising a series of field stations along the track and a control office, railway traffic governing apparatus at each said station, a line circuit connecting each of said stations with said office, a selector relay at each station, a selector relay for each station at said office, means controlled over said line circuit for simultaneously energizing the selector relay at any station and the corresponding station selector relay at the office, an auxiliary relay at the office and at each station, means for controlling all said aux-

iliary relays from the office, means controlled by the two energized selector relays when the auxiliary relays are in one position for effecting the control of the traffic governing apparatus 5 at the associated station in accordance with the position of control levers assigned to said station at the office, and other means controlled by the two energized selector relays when the auxiliary relays are in another position for indicating at 10 10 the office the condition of the traffic governing apparatus at the associated station.

56. A synchronous selector train dispatching system comprising an office and a plurality of stations, a synchronous selector at the office and 15 at each station, a centrally biased three position polar relay at each station, means for actuating the selector at the office and for successively operating all said polar relays to predetermined positions, and means controlled by each 20 polar relay and responsive to successive operations thereof for actuating the associated station selector in synchronism with the office selector but for releasing such associated selector if the polar relay remains in its biased position 25 for more than a predetermined interval of time.

57. A synchronous selector train dispatching system comprising an office and a plurality of stations connected by a line circuit, a centrally biased three position polar line relay at each station 30 included in said line circuit, a synchronous selector at said office and at each station, a two position relay device at the office, means for repeatedly operating said relay device to actuate the office selector and to repeatedly energize said 35 line circuit with currents of selected polarity, a slow release relay controlled by each said line relay, means controlled by each line relay for actuating the associated station selector in synchronism with the office selector, and means for 40 releasing each station selector if the associated slow release relay becomes released.

58. A synchronous selector train dispatching system comprising an office and a plurality of stations connected by a line circuit, a centrally 45 biased three position polar line relay at each station included in said line circuit, a synchronous selector at said office and at each station, a two position relay device at the office, means for repeatedly operating said relay device to activate the office selector and to repeatedly energize said line circuit with currents of selected polarity, a slow release relay controlled by each 50 said line relay, means at each station for progressively actuating the selector at that station 55 in response to successive operation of the associated line relay by currents of predetermined polarity, and means for restoring each station selector to its original condition if the corresponding slow release relay becomes released.

59. In a centralized traffic controlling system for railroads, a station selector comprising a centrally biased three position polar line relay, a slow release relay energized by said line relay in either of its two energized positions but not 65 in its biased position, a series of counting relays also controlled by said line relay, a pickup circuit for the first counting relay closed when said slow release relay is deenergized and the line relay is energized in one position, a pickup circuit for each succeeding odd numbered counting relay including a front contact of the preceding even numbered relay, and the same contact of the line relay, a pickup circuit for each even numbered counting relay including a front contact of the preceding odd numbered counting 70 75

relay, means for maintaining each counting relay in energized condition until the next relay picks up and then releasing it, and means for supplying said line relay with line current periodically alternating in polarity. 5

60. In a centralized traffic controlling system for railroads, a station selector comprising a normally deenergized three position polar line relay, a series of counting relays, means for energizing the first counting relay by said line relay 10 when the latter is first energized, means for energizing each succeeding odd numbered counting relay in turn over the same contact of the line relay and the front contact of the preceding even numbered relay, means for energizing each 15 even numbered relay when said line relay is energized in the opposite direction over an opposite contact of said line relay and the front contact of the preceding odd numbered relay, means for supplying said line relay with line 20 current periodically alternating in polarity to energize said counting relays consecutively, means for holding each relay picked up until the next relay is picked up, said last named means being responsive to the deenergization of said line relay to release said counting chain, and means also responsive to the deenergization of said line relay to again connect the first counting relay to the contact of said line relay closed first when 25 said line relay is again energized for a subsequent series of operations. 30

61. In combination with a movable device, a relay, transmitting means effective when operated to produce a message the character of which depends upon the position of said device, starting means effective when said relay and said device disagree in position to operate said transmitting means, and means controlled by said transmitting means and effective only if the message produced is of the character determined 35 by said device to operate said relay into agreement with said device. 40

62. In combination with a movable device, a relay, transmitting means effective when operated to produce a message the character of which depends upon the position of said device, starting means effective when said relay and said device disagree in position to operate said transmitting means, and means controlled by said transmitting means and effective upon the conclusion 45 of a message only if such message was of the character determined by said device to operate said relay into agreement with said device. 50

63. In combination with a movable device, a relay, a movable member responsive to the position of said device, transmitting means effective when operated to produce a message the character of which is determined by said movable member, starting means effective when said relay and said movable member disagree in position to operate said transmitting means, and means responding uniquely to a message of the character determined by said movable member to operate said relay into agreement with said 55 movable member. 60

64. In combination with a movable device, a relay, a movable member operated in response to a change in the position of said device, transmitting means effective when operated to produce a message the character of which is determined by said movable member, starting means effective to operate said transmitting means when said relay and said movable member disagree in position irrespective of the position 70 75

tion then occupied by said device, and means responsive to a message from said transmitting means for operating said relay.

65. In a train dispatching system of the way-side signal control type, the combination with a large number of wayside signals located along the railway track and each controlled by traffic conditions ahead, of means for controlling said signals distinctively over the same line wires comprising, a bank of relays in the dispatcher's office, a bank of relays at each of a plurality of way stations, means for operating the relays of each bank sequentially in a particular order and over an uninterrupted line circuit in such a way that corresponding relays of all the banks are operated synchronously and so that corresponding relays of all banks at all times assume corresponding positions, and a plurality of message circuits for controlling said signals closed sequentially and each including the same line wire and controlled by contacts of corresponding relays of the dispatcher's office bank and a particular way station bank.

66. In a train dispatching system of the way-side signal control type, the combination with a large number of wayside signals located along the railway track, of means for controlling said signals distinctively over the same line wires comprising, a bank of channel selecting relays in the dispatcher's office, a bank of channel selecting relays at each of a plurality of way stations, normally inactive stepping means including an uninterrupted wire running from the office to each way station for operating the relays of each bank sequentially in a particular order in such a way that corresponding relays of all banks are operated synchronously and so that corresponding relays of all banks at all times assume corresponding positions, means controllable from any way station and from said dispatcher's office for rendering said stepping means active to operate said channel selecting relays through a specific number of cycles of operation, and a plurality of message circuits for controlling said signals closed sequentially and each including the same line wire and controlled by contacts of corresponding relays of the dispatcher's office bank and a particular way station bank.

50 67. In a train dispatching system of the way-side signal control type, the combination with a large number of wayside signals located along the railway track, of means for controlling said signals distinctively over but two line wires and a common wire comprising, a bank of channel selecting relays in the dispatcher's office, a bank of channel selecting relays at each of a plurality of way stations, normally inactive stepping means for operating the relays of each bank sequentially in a particular order in such a way that corresponding relays of all banks are operated synchronously and so that corresponding relays of all banks at all times assume corresponding positions, means for rendering said stepping means active to operate said channel selecting relays through a specific plural number of cycles of operation, a plurality of message circuits for transmitting indications and controlling signals each including the same line wire and controlled by contacts of corresponding relays of the dispatcher's office bank and a particular way station bank.

68. In a dispatching system, a dispatcher's office, a plurality of stations, station selecting means including a line circuit extending to the

several stations for establishing communication between the dispatcher's office and the several stations only one at a time, said means being normally inactive in an initial condition, a device in the dispatcher's office for starting said means into operation, and means controlled over said line circuit for establishing partial circuits at each station for the control of said starting device.

69. In a dispatching system for railroads, a dispatcher's office, a plurality of way stations, a stepping circuit connecting the dispatcher's office with the several stations, means for energizing said stepping circuit with impulses of different polarities, a bank of neutral stepping relays at each station, each stepping relay having a pick-up circuit controlled by the front contact of the next preceding relay in the bank, means controlled by impulses on said stepping circuit for alternately energizing the pick-up circuits for alternate stepping relays of said bank, a message circuit connecting the dispatcher's office and said stations, and means governed by said stepping relays for controlling the energization of said message circuit at successive time intervals corresponding with the energization of said stepping circuit.

70. In a dispatching system for railroads, a dispatcher's office, a plurality of way stations, devices at each station having different operated conditions to be indicated in the dispatcher's office, a bank of neutral stepping relays at each station, means for operating said stepping relays sequentially, a message circuit extending from the dispatcher's office to the several stations, and means for rendering said devices at said stations effective only one station at a time to control the energization of said message circuit.

71. In a dispatching system for railroads, a dispatcher's office, a plurality of way stations, devices at each station having different operated conditions to be indicated in the dispatcher's office, a message circuit and a stepping circuit connecting the dispatcher's office to the several stations, means in the dispatcher's office for energizing said stepping circuit with time-spaced impulses, a bank of neutral relays at each station operated sequentially one at a time by the impulses of said stepping circuit, and means for rendering said devices at said stations effective only one station at a time to control the energization of said message circuit after each stepping operation of said bank of relays.

72. In a system for governing traffic on railroads from a central office, a field station, a stepping circuit and a message circuit connecting the field station and the central office, normally inactive impulsive means in the central office operable to energize said stepping circuit with time-spaced impulses, a bank of normally de-energized neutral stepping relays at said central office and said field station, means for energizing said stepping relays in said banks sequentially one at a time and in synchronism as said impulses are applied to the stepping circuit, a device at the field station having different operated conditions to be indicated in the central office, indication registration means in the central office, said banks of stepping relays acting to establish concurrently a circuit at the field station for rendering said device effective to control the energization of said message circuit and a circuit in the central office for rendering said indication registration means responsive to such energization of the message circuit, and means

actuated by a change in the operated condition of said device for initiating the operation of said impulsing means.

73. A selector of the relay type comprising a series of counting relays, a control relay normally at rest and having a pair of contacts closed alternately when said relay is operated repeatedly, a normally deenergized slow-release relay governed by the control relay and held in its energized position when the control relay is operated repeatedly, and operating circuits for said counting relays the circuits for consecutive relays being connected alternately to the said pair of contacts of said control relay and each except the first including a front contact of the preceding counting relay, the operating circuit for said first counting relay including a contact closed only when such normally energized relay is released whereby the first counting relay will be picked up only upon the first operation of said control relay after a period of rest and the succeeding counting relays will operate in order upon repeated operation of the control relay.

74. In combination with a control relay having a pair of contacts closed alternately when the relay is operated repeatedly, means for operating said control relay repeatedly through a series of operations, a normally deenergized slow release relay governed by said control relay and held in its energized position when the control relay is operated repeatedly, a chain of counting relays, operating circuits for said counting relays the circuits for consecutive relays including alternate ones of said pair of contacts of the control relay and each except the first including a front contact of the preceding counting relay, and means effective when said normally deenergized relay is released for placing the first counting relay under the control of the control relay, whereby the first counting relay will be energized upon the first of a series of operations of the control relay and the remaining counting relays will be energized in sequence upon succeeding operations in said series.

75. A centralized traffic controlling system for railroads including an office and a station, a three-position signal control lever at the office, a plurality of direct current polar relays of the stick type at the station, opposing signals at said station, operating circuits for said signals each including in series contacts of all said polar relays, and means for positioning each of said polar relays by momentary current impulses of current under the control of said lever for clearing a selected one of said signals or for placing all said signals at stop depending upon the position of the lever.

76. A centralized traffic controlling system for railroads including an office and a station, a three-position signal control lever at the office, a two-position switch lever at the office, a starting key at the office, a railway switch at the station and signals for governing traffic over said switch in opposite directions, three relays of the stick type at the station for governing said switch and signals, communication apparatus connecting said office and station, means responsive to a momentary operation of said starting key to initiate an operation of said communication apparatus during which one of said relays is caused to assume a position in agreement with the switch lever to operate the switch to a corresponding position, and the other two stick relays are caused to assume positions to clear a particular signal depending upon the extreme position occupied by

the signal lever or to place all signals at stop if a signal lever is in its intermediate position.

77. In combination with line wires, a movable device, a stop relay normally agreeing in position with said device, transmitting means set into operation in response to a disagreement between said device and said relay for delivering a code to said line wires, and means effective upon the completion of said code for operating said stop relay into agreement with said device.

78. A selective train dispatching system for transmitting distinctive messages from one station to another remote station, comprising a group of movable devices at one station, each device having at least two operative positions in each of which a distinctive control contact is closed, means associated with each device effective when said device is moved from one operative position to another position to initiate the transmission of a distinctive message to said remote station, means including the closed control contact of such device for completing the transmission of said distinctive message, and means at said remote station selectively responsive to said distinctive message.

79. Remote controlling apparatus comprising a movable device capable of assuming two positions, a relay having an armature normally in agreement with said device, means operating when said device is moved out of agreement with said armature to transmit a code signal to a remote point, means responsive to said code signal for moving said armature into agreement with said device, and indication means at said remote point controlled by said code signal in accordance with the position of said device.

80. Remote controlling apparatus comprising a movable device capable of assuming two positions, a relay having an armature normally in agreement with said device, means operating when said device is moved out of agreement with said armature to transmit to a remote point a code signal made up of a plurality of code elements, means responsive to a predetermined element of said code to move said armature into agreement with said device, and indication means at said remote point controlled by said code signal in accordance with the position of said device.

81. In a centralized traffic controlling system for railroads, a line circuit, a section of railway track provided with a track circuit, a first relay controlled in accordance with the condition of said track circuit, transmitting means operating when actuated to deliver to the line circuit an indication of the condition of the track circuit, a second relay controlled in accordance with the indication last transmitted to the line circuit, and means controlled by said first and second relays and effective when the condition of the track circuit disagrees with the indication last transmitted to actuate said transmitter.

82. A selector of the counting relay type comprising a control relay, a plurality of counting relays arranged in order, a pickup circuit for each odd numbered counting relay including a front contact of the next preceding relay and a contact of said control relay closed in one position, a pickup circuit for each even numbered counting relay including a front contact of the next preceding counting relay and a contact of said control relay closed in another position, and a stick circuit for each counting relay including a contact of said control relay.
